KEY SWITCH MOUNTING

Merwin J. Larsen, Villa Park, Ill., assignor, by
mesne assignments, to Central Commercial In-
dustries, Inc., Chicago, Ill., a corporation of
Delaware

Application October 14, 1949, Serial No. 121,335

6 Claims. (Cl. 84—423)

1

This invention relates to switch mounting means and has particular reference to means designed, constructed and adapted primarily for use with a piano or other keyboard musical instrument for detachably mounting a gang or assembly of electric switches upon the case of the piano in a manner to operatively relate actuators of the switches with respective playing-keys of the instrument's keyboard and whereby when playing said keys the switches will be operated, i. e. they will be "off" when the keys are raised and "on" when the keys are depressed.

A device of the character above set forth is particularly useful in combination with the type of electronic musical instrument disclosed in U. S. Letters Patent No. 2,250,065 of July 22, 1941, in which device means are employed for producing audio signals having the tone frequencies of notes associated with different playing-keys of the keyboard of a piano or other keyboard musical instrument. In said instrument, assigned playing-keys are coactive with electric switches which are connected in an electrical network and with tone frequency generators and a translating device, whereby sustained tones can be played from said keyboard as and when desired.

An instrument of the class disclosed in said Patent No. 2,250,065 has been found to be very useful if and when used with a keying mechanism capable of being readily attached to and removed from a piano so that the mechanism can be removed from a piano situated at one place and applied to a piano situated at another place such as when a traveling band, orchestra or a performer finds it costly and inconvenient to transport a piano from place to place.

An essential object of the invention is the provision of a simple, compact and inexpensive mechanism which enables an assembly of electric switches to be readily applied to or removed from any standard piano without requiring any structural alterations in the instrument.

Another object is the provision of a mechanism, the form, construction and design of which enable quick and convenient adjustment of the mechanism that insures a necessary coactive relation of the keys of the piano to the actuators of the respective electric switches.

A further object is the provision of a mechanism which, when adjusted to a piano as intended will not be subject to accidental derangement when in use.

A mechanism for attaining the above mentioned objects and others is disclosed in the accompanying drawings, in which:

Figure 1 is a view in front elevation of a piano showing the invention applied;

Figure 2 is a sectional perspective view of one embodiment of my invention;

2

Figure 3 is a view in front elevation of a portion of a piano showing the invention applied, the parts being shown on an enlarged scale;

Figure 4 is a perspective view of one of the supporting brackets;

Figure 5 is a sectional perspective view of a further embodiment of my invention;

Figure 6 is a view partly in elevation and partly in section of a still further embodiment of my invention; and

Figure 7 is a section of a portion of the U-channel bar showing one of the electric switches, the line X—X indicating the plane of a playing-key when the switch is in an "off" position.

In carrying the invention into practice and on referring to Figures 1-4, inclusive of the accompanying drawings, the device consists of a longitudinally disposed U-bar 10 of sheet steel, aluminum or other suitable material, including

20 Bakelite, the same providing a mounting for a plurality of longitudinally spaced apart electric switches 11, each having a depending actuator 12 consisting of a vertically slideable pin, the lower end of which presses lightly against a preas-

25 signed playing-key K of the keyboard of a piano P or other keyboard musical instrument. While these switches may be of any approved well known construction, it is preferred that they conform to the constructional features of the switch 30 disclosed in the patent to M. J. Larsen, et al., No. 2,487,977 of November 15, 1949. Mounted in the channel of said U-bar 10 are spaced apart bus-bars 13 and 14, the former of which is grounded at 15. Each of said electric switches comprises a

35 resilient element of conductive material such as springy wire formed with a long coil 16 functioning as a retractile spring and a short angularly disposed coil 17 functioning as a contactor and positioned so as to alternately engage and dis-

40 engage the bus-bars 13 and 14 in response to vertical motion of a playing-key when the piano is played. At the juncture of the short coil 17 with the long coil 16, the wire of which the coils are formed is attached to a vertically travelling

45 follow nut 16a of electrical insulating material in which nut, the actuator 12 is threaded for vertical adjustment. The lower end of the long coil 16 is attached to a signal input terminal 18 whereby the actuator is lightly urged in a down-

50 ward direction so that its lower end rests upon the upper surface of the playing-key at the back end thereof and whereby, as the actuator lowers upon depressing the key, the short coil 17 will shift from a position of engagement with the

55 grounded bus-bar 13 to a position of engagement with bus-bar 14 for transmission of a tone signal to an audio amplifier (not shown).

The switch assembly is herein shown as applicable to an eighty-eight note piano. For the purpose of the invention, the switch may consist of

any desired number of individual electric switches. In the instant embodiment of the invention, sixty individual switches are employed. The U-bar 10 is slightly shorter than the length of the keyboard, and, as shown, the upper and lower flanges 10a and 10b of the bar are each formed with a longitudinal slot 20. At each end of the bar is a bracket 21, shown in detail at Figures 2, 3 and 4. As the brackets are substantially identical, a description of one will suffice for the other. Each of said brackets consists of a metal stamping formed with a vertical arm 22 which extends through the vertically aligned slots 20 so that the bar 10 may be shifted horizontally when applying the device to the piano. The bracket has a horizontal flange 23, on which flange 10b of bar 10 rests. The bracket is then bent downwardly at 24 and terminates in a flat, horizontally disposed lug 25.

When attaching the device to the keyboard of the piano, the bar 10 is placed in a horizontal position at the front of the stop rail R. The brackets 21 are then adjusted to aline their lugs 25 with the respective end playing-keys. Removable wedges 26 are then inserted between the upper surfaces of the keys at the back ends thereof and the under surfaces of lugs 25, the latter being positioned beneath rail R, so as to be forced in secure engagement therewith when attaching the wedges, as aforementioned. Thus applied, the actuators are operatively related to their respective playing-keys and the entire key assembly maintained in a rigid position where it cannot be easily deranged. In this form of my invention, application of the wedges as above stated forces the front ends of the end keys down so that they are rigidly secured in these positions. These two keys are, therefore, rendered inactive and cannot be played.

The lugs 25 are each formed with an elongated slot 25a and, as shown in the embodiment at Figure 5, the slot receives a screw 25b which is driven into the stop rail R from the bottom thereof. In this embodiment, the end keys of the piano keyboard are free to be employed.

In the embodiment shown at Figure 6, the lug 25 receives a screw 28 which is driven downwardly into the key K at a point beneath the stop rail R. A spacer 30 is associated with the key guide pin 27a to stop motion of the key in a downward direction as in the first described embodiment of my invention.

While the modifications of the invention disclosed at Figures 5 and 6 require disassembling parts of the piano case in order to effect application of the device to the piano, there are instances where one or the other of these embodiments may be preferred. In each of these modifications, the key switch rail may be rigidly supported in a horizontal position where the lower end of the pin 12 of each separate switch is properly correlated to its respective playing-key. After the bar 10 has been rigidly mounted on the piano, the pins 12 may be adjusted vertically so that their lower ends rest lightly upon the playing-keys by action of the coil 16.

The bar has a removable cover plate 29. When the device is applied as shown at Figure 1, the cabling C from the signal generating and signal translating mechanism M may be run from the switches so that the mechanism may be placed at one end of the piano and supported by the floor.

In each of the several embodiments of my invention, the vertical arm 22 of the bracket is

formed with a threaded hole 30 to receive a clamp screw 31. After the brackets have been firmly secured in their intended positions and the bar 10 has been adjusted to aline the pins 12 of switches 11 with their respective playing-keys, the screws are turned so as to establish a secure binding engagement with the inner face of the vertical wall of said channel bar, thereby securing said bar against longitudinal movement.

Either one of the several disclosed embodiments represents a simple, compact, neat appearing device for effecting quick and convenient application of the switch assembly to or removal of same from the piano as and when desired.

It is, of course, understood that the brackets 21 are formed as rights and lefts and that except for this they are structurally the same. Only one of the complete key operated switches is shown but as they are identical, it suffices to say that when mounted on rail 10 in precalculated spaced relation to each other, the pins 12 are disposed so that for each black key and for each white key in the musical range of the device, they will be coactive with a respective one of said pins.

What I claim as my invention is:

1. An electric switch assembly for use with a keyboard musical instrument, said assembly comprising a longitudinal series of electric switches, a horizontally disposed rigid bar overlying said keyboard and disposed parallel thereto and on which said switches are mounted, each of said switches having an actuator adapted to be operated by a respective playing-key of said keyboard, supporting brackets for said bar, each of said brackets having a horizontally disposed lug insertable between a respective playing-key and a fixed part of said instrument, and means for and coactive with the lug of each separate bracket for securing same in a fixed position on said instrument to thereby retain said bar against movement relative to said keyboard.

2. An electric switch assembly according to claim 1, wherein said bar is adjustable vertically on said brackets.

3. An electric switch assembly according to claim 1, wherein said bar is adjustable vertically and horizontally on said brackets.

4. An electric switch assembly according to claim 1, wherein said securing means comprises wedges which are coactive with the lugs of the respective brackets and with the respective playing-keys with which said lugs are associated for forcing said lugs in clamped engagement with a fixed part of said instrument.

5. An electric switch assembly according to claim 1, wherein said securing means includes a fastening device for and coactive with the lug of each separate bracket and engageable with a fixed part of said instrument.

6. An electric switch assembly according to claim 1, wherein said securing means includes a fastening device for and coactive with the lug of each separate bracket and engageable with the respective playing-key with which said lug is associated.

MERWIN J. LARSEN.
